UNITED STATES PATENT OFFICE.

JAMES BRADY, OF BROOKLYN, NEW YORK.

PAPER-FILE.

SPECIFICATION forming part of Letters Patent No. 284,370, dated September 4, 1883.

Application filed June 10, 1882. (No model.)

To all whom it may concern:

Be it known that I, JAMES BRADY, of Brooklyn, Kings county, New York, have invented certain new and useful Improvements in Paper-Files, of which the following is a specification.

My invention applies more especially to the simple form of file for filing bills, letters, or other papers, which usually consists of a long pointed wire or needle rising from a rigid base, which is adapted to rest directly upon the desk and there receive the papers, which are simply forced down over the needle, and thus accumulated in closely-overlying layers thereon. In the usual construction the needle is rigidly socketed in the base by being screwed or driven into the same, the socket-hole being a tight, rigid fit for the socketed end of the needle-wire from the root end to the top surface of the base, where the mouth of the socket-hole presents a rigid right-angled edge to the protruding needle-wire. It hence follows, particularly where the base is made of metal, that the needle, when in use, is very likely to become broken off close to the face of the base.

This break commonly occurs when the file is much used—such as in banks or counting-rooms—where the file is frequently filled and emptied, as the frequent filing of successive papers and the removal of the mass of accumulated papers subjects the needle to repeated lateral bends or strains, which strains, owing to the rigid socket in which the needle is held, become concentrated at the rigid mouth of the socket, where the sharp, tight-fitting angular edge acts to sever it, thus necessitating frequent repairs or renewals of the needle, or the purchase of new files.

Now, my improvement aims to obviate the above-named defects; and it consists partly in forming the socket-hole with a flaring mouth, whereby the existence of an angular cutting-edge is prevented, and an elastic lateral play of the needle in the socket is allowed, thus preventing the concentration of strain on the root of the needle, and thereby obviating the breaking of the needle under any ordinary usage.

My invention also embodies some minor features, as hereinafter fully set forth.

In the drawings annexed, Figure 1 presents an elevation of my improved file, with the base portion in section to show the novel con-

struction thereof. Fig. 2 is a plan view of a detail.

In the drawings, *a* indicates the base, and *b* the needle. The base may be formed of any suitable material, but is presumed to be preferably made of cast-iron, in circular or any other of the ordinary shapes and designs. The needle *b* is preferably made of steel or spring-brass wire; but other metals may be used. The needle may be socketed directly in the base or in a socketing-plug which is inserted in the base, the latter being preferable.

The preferred form of my invention is shown in Fig. 1, where the needle is socketed in the socket-plug *c*, which is screwed into a screw-thread cavity, *d*, in the base, or otherwise engaged in the base by a tight frictional fit, or by some fastening which will serve the purpose of the screw-thread shown, which latter is, however, considered best. The needle is secured in the socket-hole of the socket-plug *c* by a tight frictional fit, or by a screw-thread engagement, as illustrated; but it will be noted that the socket-hole does not closely embrace the end of the needle throughout, but the mouth of the socket-hole is flared, thus avoiding any sharp right-angled edge around the protruding wire, and thus permitting the needle to have a limited elastic play or bend in all directions laterally, which obviously will render the needle much more durable, and prevent its breaking off close to the base, as has been the case heretofore.

The socket-plug *c* may be made of inelastic or of elastic material—for instance, of metal on the one hand or rubber on the other. If made of metal, as presumed in Fig. 1, I prefer to employ an elastic cushion or washer, *e*, of soft rubber or other similar material, which embraces the needle just above the holding-plug *c*, this washer being held between the top of the socket-cavity *d* in the base, and the top of the screw-plug *c*, which is screwed up against it, thus holding the cushion-washer in firm position, and enabling it to be compressed more or less, and thereby adjusting the grasp on the needle. In this way the root or socket end of the needle is held with an elastic yet firm grasp, and all concentration of rigid strain at any particular point of the needle is prevented; and, furthermore, the elastic grasp on the end of the needle may be increased or

decreased by screwing the plug *c* in or out, as will be understood, thus fully accomplishing the object of the invention. The screw-plug *c*, an inverted plan of which is shown in Fig. 5 2, may be readily screwed in or out by a pin-wrench, and the needle may thus be readily inserted or removed, as may be requisite; hence if a needle should ever become broken or injured by long usage, a new one may be 10 easily inserted, particularly if the needle be held simply by frictional fit in the plug *c*, or by the elastic frictional grasp of the elastic washer *e*, as will be readily appreciated.

In Fig. 1 it will be seen that the inward 15 flange forming the top or shoulder of the socket-cavity *d*, against which the cushion abuts, surrounds but does not closely embrace the needle, thereby firmly retaining the cushion, yet permitting the needle to have an 20 elastic lateral play, as will be understood.

What I claim as my invention is—

1. A file-base having a needle-socket formed with a flaring mouth and a tight-fitting root portion, with a filing-needle affixed therein at its root end, substantially as and for the purpose set forth. 25

2. The combination, with a file-base formed with a socket-cavity, of a removable plug, and a filing-needle affixed at its root end in said plug, substantially as herein set forth. 30

3. The combination, with a file-base formed with a screw-threaded cavity, of a screw-threaded plug adapted to screw into or out of said cavity, and a filing-needle affixed at its root end to said plug, substantially as herein 35 set forth.

JAMES BRADY.
